UNITED STATES PATENT OFFICE.

MILTON LIGGETT, OF SEYMORE, IOWA.

POULTRY-FEEDING DEVICE.

Application filed February 28, 1922. Serial No. 539,905.

To all whom it may concern:

Be it known that I, MILTON LIGGETT, a citizen of the United States, and resident of Seymour, in the county of Wayne and 5 State of Iowa, have invented certain new and useful Poultry-Feeding Devices, of which the following is a specification.

The object of my invention is to provide a poultry feeding device of simple, durable 10 and inexpensive construction that can be made of sheet metal with a minimum of hand work and without the use of bolts or the like in assembling.

A further object is to provide a feeding 15 device of this class comprising a trough, a hopper, and perforated plates for keeping the poultry from getting into the trough, all of which parts can be shipped knocked down and without danger of breaking and 20 can be readily, quickly and easily assembled by the operator; and

A further object is to provide a device of 25 this kind in which the hopper may be readily, quickly and easily adjusted vertically in relation to the trough and adapted to automatically feed different kinds of material in proper quantities into the trough.

My invention consists in the construction, arrangement and combination of the various 30 parts of the device, whereby the objects contemplated are attained, as hereinafter more fully set forth, pointed out in my claims, and illustrated in the accompanying drawings, in which:

35 Figure 1 shows an isometrical view of the complete feeding device assembled ready for use.

Figure 2 shows a central transverse sectional view of the same.

40 Figure 3 shows an enlarged detail view illustrating one of the tongue and slot devices for adjustably securing the hopper in position, and

45 Figure 4 shows a transverse sectional view of the feeding device in knocked down position.

Referring to the accompanying drawings I have used the reference numeral 10 to indicate a trough portion. This is preferably 50 made complete of a single piece of sheet metal and is provided at its ends near its center with two slots 11.

The hopper is indicated generally by the 55 numeral 12 and is open at its top and bottom and is tapered so that its lower end is wider than its upper end, thus preventing poultry

feed from becoming wedged therein and providing for a constant discharge of the feed as fast as it is removed from the trough. At the top edge the sides are inclined outwardly at 13 and a cover member 14 is provided, made of sheet metal, its side edges are curved downwardly and inwardly to pass around the edges 13 and provide a sliding, detachable cover which will be firmly 65 and securely held in position and be rain tight and at the same time be readily and easily removed for filling.

In the sides of the hopper 12 near each end are two lugs 14^a and 15 formed by making substantially U shaped cuts in the metal and bending the lower ends thereof slightly outward, the lugs 14^a being in a lower plane than the lugs 15. At each end of the hopper are two sheet metal tongues 16 formed of 70 the same material of which the hopper is made and designed to protect outwardly and upwardly through the slots 11. There are two sets of these tongues 16, one above the other, as shown in Figure 2.

For the purpose of supporting the hopper in position and also providing guards to prevent poultry from getting their feet in the trough I provide two curved sheet metal plates one for each side, indicated by the 75 numeral 17. These plates are provided with openings 18 through which poultry may have access to the feed in the trough. The lower edge of the plate is inclined straight downwardly at 19 and is designed to rest 80 against the inner surface of the side of the trough, and the top edge at 20 is inclined upwardly and is designed to rest against the adjacent side of the hopper and to engage one of the sets of lugs 14^a and 15, and 85 when in position these plates 17 serve to firmly brace and support the hopper against downward or lateral movement and the tongues 16 brace the hopper against upward movement so that when assembled all of the 90 parts are firmly and securely held together.

When using the hopper for kinds of food that flow readily the hopper is placed in its lowermost position and when using food that does not flow readily the hopper is 105 placed in its elevated position.

In Figure 4 I have shown the parts in their knock down condition and arranged for convenient shipping and handling where they occupy a minimum of space. When it 110 is desired to assemble the feeding device, the operator first places the hopper in position

in the trough and causes either the upper or lower set of tongues 16 to pass through the slots 11. This can be readily and easily done because the sides of the trough 10 can 5 spring outwardly to a slight extent. When the hopper has thus been placed in position at the proper elevation then the plates 17 are inserted in the position shown in Figure 2, and these plates, being made of sheet metal 10 can be sprung sufficiently to permit the upper edges thereof to enter beneath the lugs 14^a or 15, and then they will spring upwardly to form a locked connection with said lugs. In this way all of the parts are firmly 15 and securely held together without bolts or other similar fastening means.

I claim as my invention:

1. A poultry feeding device comprising in combination a trough portion, a hopper portion, the latter being formed with lugs at its sides, and two plates made of sheet metal and each shaped to enter the trough portion and engage the inner side thereof, and also to extend inwardly and upwardly with its upper edge engaging the side of the hopper portion, and also engaging the lugs thereof, to thereby firmly and securely hold the hopper and plates in position.

2. A poultry feeding device comprising in combination a trough portion, a hopper portion, the latter being formed with lugs at its sides, and two plates made of sheet metal and each shaped to enter the trough por-

tion and engage the inner side thereof, and also to extend inwardly and upwardly with 35 its upper edge engaging the side of the hopper portion, and also engaging the lugs thereof to thereby firmly and securely hold the hopper and plates in position, and means for detachably connecting the ends of the 40 hopper with the ends of the trough to prevent upward movement of the hopper.

3. A poultry feeding device comprising a sheet metal trough having slots at its ends, a hopper portion formed of sheet metal 45 tapered widest at its bottom, said hopper being provided at its ends with two sets of tongues, extending upwardly and outwardly to enter said slots, one set being in a different horizontal plane than that of the other, said 50 hopper being also provided at its sides with two plates formed of sheet metal and each being provided with openings through which poultry may insert their heads, and each comprising a curved or arched body portion 55 and also an outer edge portion designed to rest against the bottom of the trough and an inner edge portion designed to engage the hopper and also the lugs thereon, said parts being so arranged that when said plates are 60 in position the resiliency of the sheet metal of which they are formed will cause the plates to yieldingly engage the sides of the hopper, for the purposes stated.
